UNITED STATES PATENT OFFICE

115,414

DESIGN FOR A COMBINED COUPLING AND SPRAY NOZZLE

Frank F. Lindstaedt, San Francisco, Calif.

Application September 8, 1938, Serial No. 79,789

Term of patent 7 years

To all whom it may concern:

Be it known that I, Frank F. Lindstaedt, a citizen of the United States and a resident of the city of San Francisco, county of San Francisco, State of California, have invented a new, original, and ornamental Design for a Combined Coupling and Spray Nozzle, of which the following is a specification, reference being had to the accompanying drawing, forming part thereof.

Figure 1 is a side elevation of the combined coupling and spray nozzle showing my new design.

Figure 2 is a front elevation of the combined coupling and spray nozzle.

I claim:

The ornamental design for a combined coupling and spray nozzle, substantially as shown.

FRANK F. LINDSTAEDT.
